UNITED STATES PATENT OFFICE

MARIA DELLER, OF GOLDERS GREEN, LONDON, ENGLAND, ASSIGNOR TO THE SCHOLL MFG. CO., INC., OF CHICAGO, ILLINOIS, A CORPORATION OF NEW YORK

SURGICAL HOSIERY

Application filed October 5, 1931, Serial No. 566,340, and in Great Britain November 7, 1930.

This invention relates to surgical hosiery which does not contain rubber and which rely upon the manner in which the yarn is woven to secure the necessary fit and afford comfort to the wearer.

One of the principal objections to this class of hosiery resides in the difficulty experienced in putting the stocking on which necessitates unduly stretching the fabric so that there is discomfort to the wearer about the ankle, while in the regions immediately above the ankle the stocking becomes loose and does not afford the close fit which is desirable. This objection is overcome in the stocking herein by providing a greater uniformity of stretching of the article as a whole.

In overcoming these objections, the heel portion is so knitted that it comprises a region which, when the stocking is laid flat, is more or less rectangular in shape and adapted to be stretched diagonally with almost the same ease as the part which otherwise bridges the foot and ankle regions, thus conforming effectively to the shape of the foot.

In hosiery of the kind referred to, the provision of an opening or openings intermediate of the toe and ankle is unavoidable in the course of manufacture, and the disposition of such opening or openings has been variously proposed in or about the region of the heel so that the latter is more or less exposed underneath or at the sides.

One of the objects, therefore, of this invention is to provide surgical hosiery which is so knitted that when the article is worn, the opening so formed exposes only a small circular region of the heel.

Another object of the invention is to provide hosiery wherein the knitted portion about the opening or openings is so woven as to avoid discomfort to the wearer thereof when the article is in use.

Other and further important objects of this invention will be apparent from the disclosures in the specification and the accompanying drawing.

This invention (in a preferred form) is illustrated in the drawing and hereinafter more fully described:

On the drawing:

Figure 1 is a side view of a stocking which illustrates the improved heel portion.

Figure 2 is an end view thereof folded by creasing transversely and turning up the foot portion.

Figure 3 illustrates a modification of the heel portion shown in Figure 1.

Figure 4 illustrates another modification of the heel portion shown in Figure 1.

Figure 5 is a further modification in which the openings in the heel portion has been closed.

As shown on the drawing:

Referring to Figures 1 and 2, the numeral 1 designates the heel region of the stocking which is substantially square, the stitches of which run in a direction such that a diagonal extends across the greatest width of the stocking, and providing a layer which is devoid of a seam underneath the heel. The opening 3 at the back of the heel is due to the fact that the heel region 1 is knitted separately and is sewn along the line 4 to the leg portion 5. The foot portion 6 is a continuation of the knit of the heel portion 1 and the leg portion 5.

The manner in which this particular form of stocking may be produced will be understood from the following:

It is assumed that the flat knitting machine, gauge 21—12 needles per inch is to be employed and a medium size stocking produced.

After knitting the leg and ankle portions, all the stitches from the needles of the front needle bed are placed on combs and hung between the needle-beds.

With a differently colored yarn, knit two or three rounds on the rear bed of the machine so as to hold the stitches together, and then the leg portion is taken from the machine.

A separate piece is now knitted, circular work, with the same number of needles which are in action, first seven rounds placing the indicators two numbers tighter than as previously placed for the leg portion, then sixteen additional rounds are knitted, with indicators placed on the same numbers as

for the leg portion, one half round 1+1 rib, and another twenty-five and a half rounds of circular work.

For the heel portion of larger size hose, 5 three to six additional rounds should be added, while for smaller size hose it will be necessary to delete three to six rounds.

The carriage of the machine now being on the right, a half round 1+1 rib is knitted, 10 and the indicators 1 and 2 are thereupon lowered.

The stitches from the front bed of the machine are then transferred to the rear bed, and the leg portion is hung on the front 15 by transferring the stitches which are on the combs to the needles of the front bed. The foot portion is thereupon knitted.

The heel portion can also be knitted on a second machine, and then transferred with 20 combs into the first machine, whereupon in such event there is no necessity for taking the stitches from the needles of the front bed on combs and the removal of the leg portion from the machine.

25 In finishing the stocking, the stitches of the rear part of the leg, which are held together by the separately colored yarn, are sewn on by hand at both sides of the heel portion, along the line 4, whereupon the 30 ankle portion and the heel portion are joined. After this has been done, the differently colored yarn is removed.

There is now only one opening at the back 35 of the heel which is formed by the first rounds of the heel portion.

The result of the foregoing operation is a heel region 1 of double-web presenting margin at the rear opening, without seam, and merging also without seam smoothly 40 into the foot portion of the single-web, the two sewn seams running parallel to the foot portion at both sides of the heel.

If desired, the heel opening 3 may be 45 closed by subsequent hand-stitching.

45 Referring to the modification shown in Figure 3, the heel region 1^a is shown made in 1+1 rib so that it is of single-web thickness instead of double, as in the preferred construction. To accomplish this construction, 50 the necessary number of rounds of 1+1 rib are knit with the same number of needles as are in action introducing the leg portion 5.

55 Figure 4 is a direct modification of Figure 3, the heel portion 1^b being knit with a fewer 60 number of needles than previously in action, the first six rounds for example being circular with a very tight tension, followed by rounds in cardigan or half cardigan.

60 In Figure 5, a construction is shown in which there is no opening in the heel portion. To accomplish this feature, only one half of the needles previously in action are used, first one round with the first and 65 fourth pins out and second and third pins in, followed by a round with the second and

third pins out and first and fourth pins in, and so on. The piece of knitting which results is a single-web similar to circular work, but open at one side indicated at 4^a, where a joint is effected with the rest of the stocking 70 by sewing, and also sewn along the line 7.

From the foregoing, it will be seen that 75 hosiery is constructed which is strong and durable, as well as easy to don and which afford the fit necessary and desirable for the 75 purposes intended.

I am aware that many changes may be made and numerous details of construction may be varied through a wide range without departing from the principles of this 80 invention, and I, therefore, do not purpose limiting the patent granted hereon otherwise than necessitated by the prior art.

I claim as my invention:

In a stocking of the character described, 85 a leg portion, and heel portion and a foot portion, said leg portion having wales extending longitudinally thereof and terminating in a substantially horizontal line adjacent the upper edge of said heel portion, 90 said heel portion being substantially rectangular in side elevation and extending from the rear edge of the leg portion forwardly along the lower edge of the rear half of the leg portion, the lower half of the foot portion being a continuation of the heel portion and having corresponding wales disposed at substantially right angles to the rear part of the leg portion, the upper edge 95 of the heel portion being stitched along a substantially horizontal line to the lower edge of the rear part of the leg portion.

In testimony whereof I have hereunto subscribed my name at Winterthur.
